[57] CLAIM

The ornamental design for a flameless heat gun, as
shown and described.

DESCRIPTION

FIG. 1 is a front, left side, bottom, reduced, perspective
view of a flameless heat gun showing my new design;
FIG. 2 is a left side elevational view thereof, the oppo-
site side being a mirror image of the side shown;
FIG. 3 is a front elevational view thereof; and
FIG. 4 is a rear elevational view thereof.
